UNITED STATES PATENT OFFICE

155,833

DESIGN FOR AN ACCORDION OR SIMILAR ARTICLE

Roberto Pancotti, New York, N. Y.

Application March 5, 1948, Serial No. 144,910

Term of patent 14 years

(Cl. D56—1)

To all whom it may concern:

Be it known that I, Roberto Pancotti, a citizen of the United States, residing at New York city, in the county of Kings and State of New York, have invented a new, original, and ornamental Design for an Accordion or Similar Article, of which the following is a specification, reference being had to the accompanying drawing, forming part thereof.

In the drawing

Fig. 1 is a front perspective view of an accordion, showing my new design;

Fig. 2 is an end perspective view.

I claim:

The ornamental design for an accordion or similar article, as shown.

ROBERTO PANCOTTI.
